CONDUCTOR CLAMP

Floyd G. Bovard, Akron, Ohio, assignor to The
Ohio Brass Company, Mansfield, Ohio, a cor-
poration of New Jersey

Application November 11, 1936, Serial No. 110,308

8 Claims. (Cl. 173—303)

This invention relates to devices for holding the ends of hollow conductors such as are used for high potential electrical transmission lines, and has for one of its objects the provision of simple and efficient gripping mechanism for holding the end of a conductor without injury and without danger of the conductor slipping or becoming released.

A further object of the invention is to provide a device of the class named which shall be simple in its construction, economical to manufacture, easy to install, and which shall be of improved construction and operation.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is a longitudinal section of a conductor joint showing one embodiment of the present invention.

Fig. 2 is a section on line 2—2 of Fig. 1.

Fig. 3 is a section on line 3—3 of Fig. 1.

Fig. 4 is an elevation, partly in section, showing the application of the invention to a dead end clamp.

Fig. 5 is an elevation looking from the right in Fig. 4.

Fig. 6 is a view similar to Fig. 4 showing a somewhat modified form of the invention.

Fig. 7 is an elevation looking from the right in Fig. 6.

Fig. 8 is a section on line 8—8 of Fig. 6.

In Fig. 1 of the drawing, the numerals 10 and 11 represent the adjacent ends of a conductor to be joined together. The joint for connecting the two ends comprises a hollow body member 12 having end sections 13 and 14 threaded onto the opposite ends thereof, each end section having a tapered opening therein. Disposed within each end section is a wedge member 15 having its outer surface tapered to fit the inner surface of the end member and each wedge member having a cylindrical opening for receiving the respective conductor ends 10 and 11. The wedge members have slots extending inwardly from opposite ends, the slots from the opposite ends being arranged in staggered relation so that the entire member may be compressed when wedged into the conical end member.

The conductor 10, as shown in Fig. 2, is formed of helical sections or strips, the strips being

dove-tailed together and each having a longitudinally extending groove on its inner surface. These grooves form helical threads within the conductor. In order to prevent the conductor from being crushed by the wedging action of the member 15, a central plug 16 is arranged to fill the end portion of the conductor and has its outer surface formed with helical projections thereon shaped to fit the grooves on the inside of the conductor 10. The plugs 16 are provided at their inner ends with heads 17 which are arranged to slide within the opening in the body member 12. The plugs 16 are also provided with keys 18 which extend into the slots in the wedging members 15 and which also project into longitudinal slots 19 in the body member 12. Packing cups 20 are disposed at the inner sides of each of the heads 17 to prevent the escape of a pressure medium within the body member 12. These packing cups may be made of leather, rubber or other suitable packing material. The body member 12 is perforated, as shown at 21, and is provided with a valve 22 through which a pressure medium, such as grease, oil or other fluid or semi-fluid material, may be forced into the opening in the body member to move the packing members 20 and the heads 17 outwardly and to hold them in their outer positions. In the appended claims the term "hydraulic" will be used to include any suitable liquid or partially liquid pressure medium.

In assembling the device to secure the conductor ends 10 and 11 together, the end members 13 and 14 are slipped over the cable ends 10 and 11 respectively and the conical wedges are slipped into the openings in the end members surrounding the conductors. The plugs 16 are threaded into the ends of the conductors and the parts thus assembled on the conductor ends are then brought into engagement with the respective ends of the body member 12, the packing cups 20 being first moved inwardly to their innermost positions. This will permit the conductor ends and the wedging members 15 to be moved inwardly a sufficient distance to clear the end members 13 and 14 so that they may be screwed home on the body member 12. The keys 18 will now be in engagement with the slots in the wedges 15 and with the grooves 19 in the body member. A suitable pressure gun is now connected with the valve 22 and a pressure medium injected into the opening in the body member. This will force the packing cups 20 and the heads 17 outwardly, the heads 17 engaging the inner ends of the wedge members 15 and 55

forcing them tightly into the tapered openings in the end members 13 and 14. This will compress the wedge members 15 against the walls of the conductor ends 10 and 11 and firmly grip the walls of the conductor between the wedge members 15 and the pins 16. Any desired pressure for gripping the conductor ends may be secured by regulating the pressure of the medium within the body member 12. The interfitting helical formation on the surfaces of the pins 16 and the inner walls of the conductors will assist in holding the conductors in place since the pins are held from rotation and the conductors would consequently have to be rotated to be withdrawn from the clamp.

In the form of the invention shown in Figs. 4 and 5, the gripping mechanism for the conductor end is similar to that described in connection with Fig. 1 but in this figure, a single end construction is shown instead of a double connector, as in Fig. 1. In Fig. 4 the body member 23 is provided at one end with an attachment eye 24 for connecting to a suitable end support. A clip 25 is provided for connection with a jumper to continue the circuit of the conductor 10.

In the form of the invention shown in Figs. 6 and 7, the inner end of the wedging cone 26 bears against a disc 27 which engages the packing cup 28, and the inner pin 28 is made separate from the disc 27 and bears against the center of the disc. The outer end of the pin 28 is bored to receive the end of a bundle of bars or rods 29 which are twisted together and secured, as shown in broken lines at 30, within the opening in the end of the pin 28. The rods 29 are somewhat resilient and spring outwardly so as to engage the inner surface of the conductor 10. These rods extend within the conductor some distance away from the clamp and serve to reinforce the conductor adjacent the end of the clamp and prevent fatigue due to vibration. A short length of stranded cable may be used for this purpose.

In the form shown in Fig. 6, the tapered and cylindrical portions of the body member are made in one piece and a removable plug 31 is threaded into the rear end of the body member to permit the wedging mechanism to be assembled. When the parts are in place, the plug 31 may be screwed into the threaded opening in the rear end of the body member and locked in place by a locking screw 32. A flexible jumper 33 is clamped to the body member by a U-bolt 34 and a keeper piece 35.

55 I claim:

1. Means for gripping a hollow cable composed of a multiplicity of helically wound strands disposed side by side and constituting the wall of a hollow cylinder, said strands forming helical threads on the inner surface of said cable and being disposed at a sufficiently steep pitch that the dominant portion of the longitudinal stress of said cable is exerted longitudinally of said strands, said gripping means comprising a core member in immediate contact with said strands and having its outer surface threaded to fit the threads on the inner surface of said cable and means for clamping said cable on said core member.

70 2. Means for gripping a hollow cable composed of a multiplicity of helically wound strands disposed side by side to form the walls of a hollow cylinder, the strands having a sufficiently steep pitch to receive longitudinally thereof the dominant portion of the longitudinal stress on said

cable, the contour of the individual strands forming threads on the inner surface of said cable, said gripping means comprising a core member threaded to fit the threads in said cable, a wedge member engaging the outer surface of said cable about said core member, and a tapered socket member engaging said wedge member.

75 3. A cable holder comprising an electrical connector having a hollow body with a tapered socket at one end thereof for receiving said cable, a compressible conical wedge surrounding said cable in said socket, a core member disposed within said cable, and hydraulic pressure means for pressing said core member, cable and wedge into said tapered socket to compress said wedge on said cable and grip the wall of said cable between said wedge and said core member.

4. A cable holder comprising an electrical connector having a hollow body with a tapered socket at one end thereof for receiving a hollow cable, a wedge member disposed in said socket about said cable, a core member disposed in said cable within said wedge member, a piston in said body member having bearing connection with said wedge member, and means for introducing a hydraulic pressure transmission medium under pressure into said body member to move said piston and force said wedge member into said tapered socket.

5. A cable holder comprising a body member having a tapered socket for receiving a hollow cable having helical grooves in the inner surface thereof, a core member disposed in said cable and having its outer surface shaped to conform to the inner surface of said cable, a wedge member disposed in said socket for engaging the outer surface of said cable, means for forcing said wedge member into said socket, and means for preventing rotation of said core member relative to said body member.

40 6. A cable holder comprising a hollow body member having a tapered socket at one end thereof for receiving a hollow cable formed with helical grooves on its inner surface, a wedge member disposed in said socket about said cable, a core member disposed in said cable and shaped to fit the helical grooves in said cable, a piston having bearing connection with said core member and said wedge member, means for applying hydraulic pressure to said piston to force said cable, core member and wedge member into said tapered socket, and means for preventing rotation of said core member and wedge member relative to said body member.

55 7. The combination with a hollow conductor, of a support therefor, and a resilient insert arranged in said conductor adjacent said support for counteracting the effects of vibration on said conductor said insert comprising a multiplicity of elongated members secured at one end to said support and resiliently spread outwardly against the inner surface of said conductor.

60 8. The combination with a hollow conductor, of a support for said conductor comprising a core disposed within said conductor, and means for gripping the wall of said conductor against said core, and a resilient reinforcement disposed within said conductor and connected to said core for offsetting the effects of vibration on said conductor at its point of support said reinforcement comprising a short length of stranded cable connected at one end to said core, the strands of said cable being resiliently spread into contact with the interior of said conductor.
